UNITED STATES PATENT OFFICE

JOSEPH SCHAUDE, OF BROOKLYN, NEW YORK

REFLECTOR SIGN

Application filed October 22, 1928. Serial No. 314,229.

This invention relates to improvements in reflector signs.

The primary object of the invention resides in a reflector sign which may be illuminated by daylight during daytime and by artificial light means at night to enable the sign to be displayed at all times. It will be appreciated that the present construction of reflector signs are only applicable for use in daylight which 10 renders them useless at night with the result that an advertiser does not derive the maximum amount of display.

Another object of the invention is to provide an artificial light attachment for the 15 present construction of daylight reflector signs which includes an electric light housing adapted to be compactly folded against the back of the sign during daytime so as not to interfere with the reflection of sunlight onto the 20 sign, and which may be readily swung to a position to reflect the rays of an electric light thereon during a night display of the sign.

With these and other objects in view, the 25 invention resides in certain novel construction and combination and arrangement of parts, the essential features of which are hereinafter fully described, are particularly pointed out in the appended claims, and are illustrated 30 in the accompanying drawing, in which:—

Figure 1 is a perspective view of my improved reflector sign with the artificial light housing in operative position.

Figure 2 is a vertical longitudinal sectional 35 view therethrough.

Figure 3 is a vertical transverse sectional view on the line 3—3 of Figure 2 showing the artificial light housing in a folded inoperative position in dotted lines.

Figure 4 is a detail vertical sectional view 40 on the line 4—4 of Figure 3.

Referring to the drawing by reference characters, the numeral 10 designates a daylight reflector sign of the ordinary well-known construction which includes an elongated casing 11 open at its front and closed at its ends, while an opaque sign plate 12 is mounted in the top thereof. The plate 12 is of glass and has the sign characters thereon which are 45 transparent or translucent and may be of any 50

desired colors for reflection by light rays onto a mirror 13 mounted in the casing at an approximate angle of 45°, whereupon the reflected transparent sign indicia from the sign plate 12 may be visibly seen by looking into 55 the open front of the casing. These signs have proven popular for daylight display but at night they have proven useless for lack of the necessary light to effect reflection. My attachment for night reflection will now be explained.

My improved attachment comprises a light-proof housing 14 which embodies top and bottom frames 15 and 16 which are foldable toward each other and connected by hingedly 65 connected links 17, which links when extended serve as braces for supporting the frames in spaced relation. The frame 16 is open and is of a size to snugly fit the top of the casing 11, while the top frame 15 is smaller in width 70 but of the same length to cause the light-proof flexible covering 18 which is connected to the two frames to assume a pyramidal shape in cross section. The light proof covering 18 75 may be leather or other similar flexible material to prevent the outward penetration of light from electric lamps 19 carried by electric sockets 20 depending from the top of the light housing. The top of the light housing has a mirror or other reflecting element 21 80 mounted therein while conical reflectors 22 supported by the sockets 20 coact with the mirror to throw the rays of the electric lamps downward onto the top of the daylight sign.

The housing 14 is movable to a position 85 behind the casing 11 by providing the vertical tracks 23 rearward of the casing and which are closed at opposite ends with the top ends of the tracks extending above the top of the casing. The sides of the bottom frame 16 are provided with outwardly projecting pins 24 which enter the slots to slidably connect the light housing to the sign casing. In the drawing, the light housing is shown 90 in full lines as in an operative position over the top of the sign casing where it is held by spring catches 25. To move the same to an inoperative position, the catches are released and the housing swung backward for 95 a distance of ninety degrees and then slid 100

downward to the position shown in dotted lines in Figure 3. The rule joints between the hinged links 17 are broken so that the top frame 15 may be collapsed to a compact 5 position against the bottom frame 16. To move the collapsible light housing to an operative position the procedure is opposite to that just described.

The sign is rigidly mounted in brackets 26 10 to support the top of the casing on a substantially horizontal plane.

From the foregoing description, it will be seen that I have constructed an attachment by which artificial light may be reflected onto 15 a reflector sign for visibly displaying the sign indicia at night, and which attachment may be moved to a position to allow the sign to function as a daylight sign when conditions demand.

20 While I have described what I deem to be the most desirable embodiment of my invention, it is obvious that many of the details may be varied without in any way departing from the spirit of my invention, and I therefore do not limit myself to the exact details 25 of construction herein set forth nor to anything less than the whole of my invention limited only by the appended claims.

What is claimed as new is:—

30 1. A reflector sign comprising a casing, an opaque sign plate having transparent indicia thereon, a mirror arranged within said casing at an angle with respect to said opaque sign plate, a collapsible housing supported 35 upon the top of said casing, and light producing means within said housing for illuminating the same to reflect the transparent indicia from said plate onto said mirror, and means for mounting said housing upon said casing 40 to facilitate the movement of the same to a position behind said casing and clear of the top for permitting natural light to reflect the sign indicia on said mirror.

45 2. In combination with a daylight reflecting sign including a casing, an opaque sign plate having transparent indicia thereon, a mirror arranged within said casing at an angle with respect to said opaque sign plate, vertical tracks at the rear of the side walls 50 of said casing, a collapsible housing slidably mounted in said tracks for movement to an operative position over the top of said casing or to an inoperative position behind said casing, foldable means for holding said collapsible housing in set-up condition when in 55 operative position, locking means for holding said housing in an operative position, and artificial light producing means within said housing for illuminating the same to reflect the transparent indicia from said plate onto 60 said mirror when said housing is in operative position thereabove.

In testimony whereof I have affixed my signature.
